CLAIM

The ornamental design for a helmet holder as shown and described.

DESCRIPTION

FIG. 1 is a perspective view of a helmet holder showing my new design;

FIG. 2 is a right side elevational view thereof;

FIG. 3 is a front side elevational view thereof;

FIG. 4 is a rear side elevational view thereof;

FIG. 5 is a top plan view thereof;

FIG. 6 is a bottom plan view thereof; and,

FIG. 7 is a perspective view thereof.

The broken lines shown in the drawings illustrate portions of the helmet holder that form no part of the claimed design. Additional broken lines in FIG. 7 illustrate environment and form no part of the claimed design.

1 Claim, 5 Drawing Sheets
